United States Patent Office

Des. 207,538

Patented May 2, 1967

207,538

GOLF PUTTER

Carl Burkland, 2630 Broadway NE, Apt. 41,
Salem, Oreg. 97303

Filed Oct. 2, 1964, Ser. No. 82,003

Term of patent 14 years

(Cl. D34—5)

FIG. 1.

FIG. 2.

FIG. 3.

FIG. 4.

FIG. 1 is a perspective view of the present golf putter showing my new design.

FIG. 2 is a putting end view of the golf putter.

FIG. 3 is a side elevation of said golf putter; and
FIG. 4 is a top view of said golf putter.

I claim:

The ornamental design for a golf putter, as shown.
